UNITED STATES PATENT OFFICE

RICHARD F. ABBÉ, OF NEW YORK, N. Y.

TUBE OR PEBBLE MILL.

No. 863,483.

Specification of Letters Patent.

Patented Aug. 13, 1907.

Application filed July 8, 1905. Serial No. 268,768.

To all whom it may concern:

Be it known that I, RICHARD F. ABBÉ, a citizen of the United States, and a resident of the borough of Manhattan, city and State of New York, have invented certain new and useful Improvements in Tube, or Pebble Mills, of which the following is a specification.

My invention relates to tube or pebble mills in which stones or pebbles, etc., in motion are used for grinding and pulverizing such materials as cement, 10 ores, chemicals, metal borings, vegetable roots, barks, etc.: and more particularly to an improved construction of such mills whereby I obtain a balancing about a center of rotation of the loads within a plurality of pebble tubes or cylinders and at the same time secure 15 an automatic feeding of the materials to be ground into and out of the various tubes while in motion.

My mill has the advantages of a maximum capacity with a minimum of turning effort, and moreover attains these results along with a constant automatic 20 feed of the materials through the mill as it operates.

One form of construction whereby I secure these effects is illustrated in the accompanying drawings in which

Figure 1 is a vertical longitudinal section, partly in 25 elevation, through the line 1—1 of Fig. 2 looking in the direction of the arrow; Fig. 2 is an end elevation of the apparatus shown in Fig. 1 with the right hand bearing omitted; Figs. 3 to 10 inclusive are enlarged detail views of various parts of the apparatus,—Fig. 4 30 being a plan view of a conduit, Fig. 3 an end view of the same conduit seen in the direction of the arrow in Fig. 4, Fig. 6 a side elevation of a gudgeon, Fig. 5 a bottom plan view of said gudgeon seen in the direction of the arrow on Fig. 6,—Figs. 7 and 8 side and end 35 views, respectively, of a device hereinafter designated a saddle, and Figs. 9 and 10, a side and top view, respectively, of a guide device. Fig. 11 is an end view of one of the cylinders with the parts connected therewith removed. Fig. 12 is a sectional view, partly in 40 elevation, to show a modified form of spiral ridges; and Fig. 13, a view of Fig. 12 on the line 13 looking in the direction of the arrow.

In the construction illustrated, I show three tubes or cylinders, A, B, C, bound together and mounted to 45 rotate about a common axis. I do not limit myself, however, to this particular number of cylinders since most any plurality of cylinders may be employed to secure the effects of my invention. In my preferred construction I secure the cylinders symmetrically as 50 shown about a shaft 1 in such manner to rotate as therewith. Upon this shaft are secured gudgeons or hollow members 2—2, which in turn rotate in the bearings 3—3.

The gudgeons are each secured rigidly to the ends of the shaft, preferably by providing a square hole 4 (see 55 Fig. 5) in the bottoms of the gudgeons and a square portion 5 on each end of the shaft to fit said square

holes. This secures the gudgeons against rotary motion on the shaft, while the shoulders 6 and nuts 7 and 8 secure them against longitudinal motion.

The means for securing the cylinders rigidly to the 60 shaft comprise, 1st, a device 9 which I conveniently call a saddle and which in the case of three cylinders is triangular in general cross-section, the faces of the triangle being curved to conform with the curvature of the cylinders. A central hole 10 is provided in the 65 saddle to receive the shaft 1. The band 11 surrounds the cylinders and is provided with a suitable connecting device 12 to join its free ends. This band, when tightened acts in an obvious manner to bind the cylinders rigidly together against the curved sides of the 70 saddle.

The cylinders are further secured together by means of bolts passed through holes 13 (see Fig. 11) in the heads 14 of the cylinders and through corresponding holes 15 (see Fig. 5) in the flanges of the gudgeons. 75 Compare Fig. 2, which shows these parts assembled. In this way I secure rigidly together the shaft, the gudgeons, and the three cylinders with the latter symmetrically disposed about the shaft. Obviously, however, other means for binding these parts together 80 may be employed. It may further be noted that increasing the length of the cylinders may require increasing the number of saddles and binding straps in order to properly support the middle portions of the lengthened cylinders.

To rotate the cylinders, shaft and gudgeons on the bearings 3—3, I prefer to key a gear-wheel 16 on the left hand gudgeon (see Fig. 1). This gear wheel meshes with a pinion 17 which in turn is rigid on the same shaft with the driving pulley 18. Obviously, when the 90 driving pulley is driven in the direction of the arrow in Fig. 2, the gear wheel 16 and the cylinders will be caused to rotate in the opposite direction.

In the hollow interior of the gudgeons I provide spiral ridges 19 which may be fitted and secured therein in 95 any suitable manner. The twist of these spirals is such as to cause them to both deliver in the same direction when the gudgeons are rotated. Thus the left hand spiral in Fig. 1 delivers to the right towards the cylinders and the right hand spiral delivers also to the right 100 and consequently away from the cylinders.

Openings 20 are provided in both heads of each cylinder, the left hand openings in Fig. 1 constituting the entrance openings and the right hand the exit openings. These openings in the cylinders connect 105 with the interiors of the gudgeons by means of conduits 21. A pair of these conduits is shown in cross-section in Fig. 1. A detached conduit is shown in elevation in Figs. 3 and 4, Fig. 3 being an end view and Fig. 4 a top plan view. It will be noted that these conduits are 110 semi-circular in cross-section, but, of course, this is not an essential feature. However, I prefer to use the con-

duit shown, since it is efficient, compact and easily constructed. These conduits are secured in place by bolts passed through holes 22 in the flanges of the conduits, (see Fig. 2 and 4) and through corresponding holes 23 in the ends of the cylinders. As shown, the flat side of the conduits rests against the ends of the cylinders with the semicircular openings 24 of the conduits connecting with inclined passageways 25 through the walls of the gudgeons. The openings at the other end of the conduits are circular in outline in the construction shown (see Fig. 2) and communicate with the openings in the ends of the cylinders. Since there are three of these conduits at each end of the mill shown, there are necessarily three of these inclined passageways 25 in each gudgeon. These are symmetrically disposed as will be seen from an inspection of Fig. 5 which is an end elevation of the gudgeon shown in Fig. 6, looking in the direction of the arrow.

Secured to the right hand end (see Fig. 1) of the shaft 20 1 between the nuts 7 and 8 is a so-called guiding device 26. This is shown in side elevation in Fig. 9 and in top plan view in Fig. 10 and may consist of metal formed in any suitable manner into the shape shown, which may be conveniently described as comprising a top portion 25 27 having a circular opening 28 and inclined side portions 29 connecting with said top portion. The interior of the guiding device shown is hollow.

The device is secured to the end of the shaft by inserting the shaft through the hole 28 in the device with 30 the nut 7 in its interior. The other nut 8 is then screwed into place and secures and clamps the device rigid on the shaft. The device is so positioned that its inclined faces 29 are opposite the inclined passageways in the gudgeon,—that is to say in the position shown in Fig. 2.

Any convenient means may be employed for initially delivering the raw material to be ground into the left hand gudgeon in Fig. 1,—such means forming no essential part of my present invention. In Fig. 1 40 these means comprise a hopper 30 delivering through certain apparatus adapted to regulate the quantity of raw material delivered from the hopper down the inclined pipe 31 into the left hand gudgeon.

In Fig. 1 a spiral ridge 19 is shown in the left hand 45 gudgeon of substantially identical construction with that shown in the right hand gudgeon. I prefer, however, to employ in the left hand gudgeon the construction of spiral ridges illustrated in Figs. 12 and 13, where in three spiral ridges 32 are provided, each making approximately a third of a turn in the interior of the gudgeon, and each being so located as to deliver the material into one of the inclined passageways in the gudgeon. Such construction of the spirals in the left hand gudgeon is to be preferred over that shown in Fig. 1, because the 55 single spiral of Fig. 1 will tend to deliver the material in greater proportion to that passageway in the gudgeon which is located immediately ahead of the delivery end of the spiral.

The operation of the foregoing devices will now be 60 described. The cylinders having been filled through manholes x with the required quantity of pebbles or other grinding materials, and having been set in motion, the raw materials are delivered down the inclined pipe 31 into the left hand gudgeon so that they fall upon the 65 spiral ridges secured to the interior thereof, which

thereupon by screw action automatically feed the materials toward the conduits, leading to the cylinders. The effect of this is to cause the fed materials to drop by gravity into those conduits that happen in the course of rotation to be below the level of the gudgeon. Thus 70 in Fig. 2 the material would drop into the two cylinders B, C the upper cylinder, of course, receiving nothing. In this way the cylinders are constantly and automatically receiving materials to be ground, as they are fed forward by screw action through the gudgeon. The 75 materials after they drop into the cylinders are thereupon ground and pulverized as in an ordinary pebble mill. This action will continue until the material accumulates sufficiently to reach the openings 20 in the right hand ends of the cylinders when said cylinders 80 are in the position of A in Fig. 1. At such time portions of the material in this cylinder will overflow and fall through its conduit into the right hand gudgeon. Of course, the other two cylinders when in the position shown in Figs. 1 and 2 will not deliver anything into 85 the right hand gudgeon because they are both located at this particular moment below the level of said gudgeon. As the material falls from each cylinder when in its uppermost position, the tendency would be for such material to fall, at least in part, down through 90 the conduits connecting the gudgeon with the lower cylinders, were it not for the guiding device 26. The inclined surfaces 29 of this device act to receive the material as it falls and to direct same away from said lower conduits and upon the spiral ridges in the interior 95 of the gudgeon.

What I claim is:—

1. In a pebble mill, the combination of a plurality of receptacles secured together about an axis of rotation and each provided with an entrance opening and an exit opening, means for rotating said receptacles about said axis, a gudgeon at each end of said receptacles and rotatable therewith, conduits leading from one gudgeon to the entrance openings of the receptacles, conduits leading from the exit openings of the receptacles to the other gudgeon 105 and spiral ridges secured in the interior of each gudgeon.

2. In a pebble mill, the combination of a plurality of receptacles secured together about an axis of rotation and each receptacle having an entrance and an exit opening, means for rotating said receptacles about said axis, a gudgeon at each end of the receptacles and rotatable therewith, conduits leading from one gudgeon to the entrance 110 openings of the receptacles, and conduits leading from the exit openings of the receptacles to the other gudgeon.

3. In a pebble mill, the combination of a plurality of receptacles secured together about an axis of rotation and each receptacle having an entrance opening and an exit opening, a gudgeon at each end of the receptacles and rotatable therewith, means for rotating said receptacles and gudgeons about said axis, conduits leading from one gudgeon to the entrance openings of the receptacles, conduits leading from the exit openings of the receptacles to the other gudgeon, guiding means in the interior of said last named gudgeon to prevent material falling out of a conduit in an elevated position from passing into a conduit or conduits in depressed position, and spiral ridges in the interior 120 of each gudgeon.

4. In a pebble mill, the combination of a plurality of receptacles secured together about an axis of rotation and each provided with an entrance opening at one end and an exit opening at the other end, means for rotating said receptacles about said axis, a gudgeon at the exit end of said receptacles rotatable therewith, conduits leading from the exit openings of the receptacles to said gudgeon and a guiding device comprising a plate with a plurality of inclined 130 surfaces secured within said gudgeon for deflecting material falling from any one conduit away from the other conduits.

5. In a pebble mill, the combination of a rotary shaft, a plurality of receptacles secured together to said shaft, each receptacle having an entrance opening at one end and an exit opening at its other end, and said shaft having a 5 square portion adjacent each end of said receptacles and threaded end portions, a pair of gudgeons having square openings fitting on the squared portions of said shaft, nuts fitting on the threaded portions of said shaft to clamp the gudgeons against the ends of the receptacles, and conduits 10 leading from the respective gudgeons to the entrance and exit openings, respectively, of said receptacles.
6. In a pebble mill, the combination of a plurality of receptacles secured together about an axis of rotation, and each provided with an entrance opening at one end and an 15 exit opening at its other end, means for rotating said receptacles about said axis, a gudgeon at the entrance end of said receptacles rotatable therewith, triple spiral ribs in the interior of said gudgeon, means for feeding the material to be treated on to said spiral ribs, and conduits leading from said gudgeon to the entrance openings of all of 20 said receptacles.

In testimony whereof, I have signed my name to this specification in the presence of two subscribing witnesses.

RICHARD F. ABBÉ.
